UNITED STATES PATENT OFFICE.

WILLIAM G. ROEPKE, OF HUDSON, WISCONSIN.

BRUSH.

1,407,674.

Specification of Letters Patent. Patented Feb. 21, 1922.

Application filed April 13, 1921. Serial No. 460,971.

To all whom it may concern:

Be it known that I, WILLIAM G. ROEPKE, a citizen of the United States, residing at Hudson, in the county of St. Croix and 5 State of Wisconsin, have invented certain new and useful Improvements in Brushes, of which the following is a specification.

This invention relates to brushes of special construction and more particularly to 10 the type, having bristles arranged to contactingly encompass an annular section of pipe or other elongated cylindrical body, for the purpose of scouring the same, an object 15 of the invention being, the provision of a cheap, strong, sanitary and efficient brush for use in cleaning the rotary coils of sterilizing tanks in creameries. Brushes of various sorts are being used for this purpose, including the ordinary scrub brush, but all 20 are more or less unsatisfactory, in that their use is slow, tedious and uncertain, parts of the surface in many instances accidentally remaining untouched. As these coils are 25 very hot, incrustation takes place, leaving a tenacious crust on the surface thereof, requiring a brush of stiff bristles to dislodge it.

As these coils are mounted on a central rotating shaft, and have, at intervals, radial supporting struts extending from the latter, 30 and are coiled to a relatively small pitch, ordinary scrub brushes are too bulky for economic use in the restricted space between the individual coils, while a flexible brush, 35 formed of a plurality of connected individual flat brushes, cannot be successfully used, because the bristles do not radiate to the center of the pipe, nor can the latter be effectively contactingly surrounded by the same, as the struts will block its continuous 40 travel from one end of the moving coil to the other.

An object of my invention, is to provide a brush with relatively stiff bristles, which 45 may be held by hand against the revolving coil to bring the latter in frictional surrounding relation with the coiled pipe, and which is constructed so as to be swingingly separable to permit the struts to pass between the members constituting the brush, 50 without removing the latter from operative position, as the operator propels the brush along the helix described by the coil.

To this end, the invention consists in the construction, combination and arrangement 55 of parts hereinafter described and claimed.

In the drawings forming part of this specification:

Figure 1 is a perspective view of a brush embodying my invention.

Figure 2 is a side view drawn to a reduced scale, showing the bristle side of the brush members.

Figure 3 is a side view of the invention showing it in its normal open position, and the manner of applying it to the pipe.

Figure 4 is a fragmentary perspective view of a coil, showing the device in operative position.

Figure 5 is a plan view of the hinge staple, and

Figure 6 is a sectional view of a round strut, showing it in engagement with the jaw formed by the brush members.

The invention, as shown, comprises two segmental brush members, A of similar 75 form, each describing approximately a semi-circle, said brush members being hinged together, preferably by a U-shaped staple B, the legs of the latter being parallel and constituting pintles rotatably projected, one 80 through each of the brush members, at a position adjacent the extremity thereof, whereby the brush members are rendered swingable away from each other, preferably to a limited degree, and toward each other into 85 contacting relation at their opposite free ends 2. The rounded ends 3, of the brush members, are non-concentric relative to the pintles 1, so that when the members are swung outwardly said ends will contact with 90 each other to restrict said outward movement. A spring 4 straddling the hinge connection, is formed with outwardly diverging arms 5, suitably secured, as by the sharpened peg end 6 in the respective brush 95 members, whereby the latter are held normally in spread position as indicated in Figure 3. The ends 2 are preferably cut radial relative to the central bore or circular open ended chamber 7, formed by the two brush 100 members, when said ends are closely adjacent each other. Extending from the arcuate walls of the chamber 7, and suitably distributed thereover and in radial relation thereto, are the bristle tufts 8, the latter being secured in the usual way (not shown) in the semi-circular shaped shells 9 forming the bodies of the brush members. The shells 9, are of parallel width, each being formed with a handle 10, whereby to facilitate the 110

manipulation of the brush when in use. It will be noted, that the handle is integral and disposed longitudinally of the bore 7, so that in manufacturing the shells great advantage is afforded, inasmuch as the shells may be easily and quickly cut out of a plank on a band saw. Referring now to Figure 4, (wherein the parts are semi-diagrammatically indicated) C designates a tank, and D a horizontal shaft rotatably supported thereon. Extending radially from the shaft are the strut supports E, whereon is supported the heating coil F. A—A designates the brush members, being pressed in surrounding relation against the circumferential surface of the coiled pipe, the hands of the operator being shown in dotted lines. As the coil revolves and threads its way through the brush, the operator walks along side accordingly, holding the brush members firmly, (against the stress of the spring 4) around the pipe. As the struts are encountered, the operator permits the brush members to slightly separate, under the action of the spring, to permit the strut to pass therebetween, the ends 2 of the shells 9 being cut away at an angle at 11 to form together a V-shaped jaw 12, whereby to facilitate the entrance of the struts.

30 The legs 1 of the hinge staple have suitable notches 13, whereby they may be bent at right angles to hold the hinge against withdrawal.

35 The hinged brush members may be said to form a split ring, each member constituting a segmental brush with convex back.

I claim:

1. A brush comprising a plurality of brush members each of arcuate form and

having bristles extending inwardly from their concave faces, each brush member being formed with an opening extending in an axial direction adjacent one edge, a substantially U-shaped pintle member passed through the openings for hingedly connecting the brush members, the edges of the brush members between the legs of the pintle member coacting to limit the opening movement of the brush members, and means for urging the brush members closed.

2. A brush comprising arcuate brush members hingedly connected together, each member having a peripheral rib extending lengthwise thereof and intermediate its side edges to provide manipulating handles, and a spring extending across the hinge connection between the brush members and arranged outwardly thereof, the terminals of the spring being anchored to the respective members.

3. A brush comprising segmental brush members, means arranged within the body lines of the brush members and inwardly from the meeting edges thereof for hingedly connecting said brush members, a coil spring disposed outwardly of the meeting edges and having its terminals extending in opposite directions and beyond said means and anchored to the respective brush members, each brush member being formed adjacent the point of securement of the spring terminal with a raised hand grip extending lengthwise of the member.

In testimony whereof I affix my signature in presence of a witness.

WILLIAM G. ROEPKE.

Witness:

GEORGE VOELKER.
